UNITED STATES PATENT OFFICE.

ROBERT HEARNS, OF ST. PAUL, MINNESOTA.

NON-REFILLABLE BOTTLE.

SPECIFICATION forming part of Letters Patent No. 742,985, dated November 3, 1903.

Application filed March 10, 1903. Serial No. 147,073. (No model.)

To all whom it may concern:

Be it known that I, ROBERT HEARNS, a citizen of the United States, residing at St. Paul, in the county of Ramsey and State of Minnesota, have invented certain new and useful Improvements in Non-Refillable Bottles, of which the following is a specification.

My invention relates to improvements in non-refillable bottles of that construction in which the valve is normally held in closed position by a weight, but which will permit the liquid to pass from the bottle when the bottle is held in pouring position and which will prevent refilling of the bottle.

15 In the accompanying drawings, forming part of this specification, Figure 1 is a longitudinal cross-section of the bottle embodying my features of invention. Fig. 2 is a view of the plug forming part of the closing means. 20 Fig. 3 is a top view of a spring forming part of my invention. Fig. 4 is a view of a valve-plug closing the bottom of the bottle-neck, and Fig. 5 is a view of a valve-disk which operates with said plug.

25 In the drawings, A represents a bottle. The lower portion of the bottle-neck is formed with an inwardly-inclined shoulder 2, forming a seat for the tapering valve-plug 3, a washer 4 being interposed between the plug 30 and seat. The washer 4 is of relatively soft material, so as to constitute a tight joint even though there be small irregularities in the plug or bottle-neck. The valve-plug 3 is formed with a series of openings 5. Said plug 35 is also formed with a central opening 6, through which passes a cord 7, supporting at its lower end a weight 8 and secured at its upper end to a disk 9, preferably of cork, which normally covers the openings 5. The 40 disk 9 is provided with a series of peripheral grooves 10, forming openings to allow the liquid to pass from the openings 5 around the disk when the parts are in the positions shown in dotted line in Fig. 1. The upper end of 45 the bottle-neck is closed by a plug 11, normally held in closing position by an irregular-shaped spring 12, which fits in a groove 13 in the plug and projects into a groove 14 in the bottle-neck. The groove 13 communicates 50 with the space below the plug 11 by the opening 15 and with the space above the plug by

ports or openings 16. The lower valve-plug is held to its seat by a U-shaped spring 17, the ends of which extend through opposite grooves 10 of the disk 9 and bear upon the 55 top of the lower valve-plug, as shown in Fig. 1. The upper plug bears centrally upon the spring 17 to compress the same, as shown.

In use, with the bottle filled and the parts in position as shown in Fig. 1, the bottle can 60 be emptied by being turned into inverted position. When the bottle is turned into inverted position, the liquid will pass through the openings in the valve-plug, carrying the disk 9 to the dotted-line position shown, and 65 passing around said disk and through the openings in the upper plug 11. When the bottle is in upright position, the weight 8 will hold the disk 9 in contact with the top of the valve-plug, closing the openings 5 and 70 preventing any liquid being forced into the bottle. The spring 17, interposed between the two plugs, will hold the lower or valve plug firmly upon its seat.

Having now described my invention, what 75 I claim as new, and desire to secure by Letters Patent, is—

1. In combination with the neck of a bottle formed at its lower end with an inwardly-beveled shoulder, a valve-plug seated upon 80 said shoulder and formed with a series of openings, a disk loosely arranged upon said plug and provided with a series of peripheral openings, a weight flexibly supported from said disk, and a plug secured in said bottle-neck above said valve-plug.

2. In combination with the neck of a bottle formed at its lower end with an inwardly-beveled shoulder, a valve-plug seated upon 90 said shoulder and formed with a series of openings, a disk loosely arranged upon said plug and normally closing said openings, said disk being formed with a series of peripheral openings, a weight flexibly supported from said disk, a plug arranged in the upper portion of said bottle-neck and provided with a series of openings, a locking-spring arranged in registering grooves in the upper plug and bottle-neck, and a spring interposed between 95 said upper and lower plugs, the ends of said 100 spring extending through opposite openings in said disk and bearing upon the plug below.

3. In combination with the neck of a bottle formed at its lower end with an inwardly-beveled shoulder, a valve-plug seated upon said shoulder and formed with a series of 5 openings, a relatively soft washer interposed between said valve-plug and shoulder, a disk loosely arranged upon said plug and provided with a series of peripheral openings, a weight flexibly supported from said disk and a plug secured in said bottle-neck above said valve-plug.
- In testimony whereof I affix my signature in presence of two witnesses.

ROBERT HEARNS.
